UNITED STATES PATENT OFFICE

ADOLPH K. HANSON, OF CHICAGO, ILLINOIS

BLADE SHARPENER

Application filed August 7, 1926. Serial No. 127,817.

This invention relates to blade sharpeners of the type wherein the blade to be sharpened is drawn at an angle across the edges of a plurality of discs in a manner to remove a thin sliver of the blade material and is adaptable particularly for use in sharpening the blades of knives, shears, etc.

One of the objects of the invention is to provide a sharpener having a plurality of series of rotatably mounted polygonal shaped discs adapted to co-operate in a manner to form a recess through which a blade may be drawn for sharpening the cutting edge thereof.

Another object of the invention is to provide a device wherein the construction and arrangement of the various elements is such that when a knife blade or the like is pressed into and drawn through the recess formed by the edges of the discs the operative sharpening faces of said discs will be positioned automatically with respect to the blade and forced against the sides of the blade to provide effective sharpening contact therewith.

A further object of the invention is to provide a construction and arrangement wherein the discs are permitted to rotate on their axes to provide efficient sharpening action of the co-operating sharpening faces, but limited in their rotation in a manner to retain the desired sharpening faces of the respective series of discs in co-operative relationship.

A further object of the present invention is to provide a construction wherein the discs may be permitted to rotate freely on their axes to bring new or unused sharpening faces of the respective series of discs into co-operative relationship and to secure them in desired position, and at the same time to allow sufficient rotary movement of the discs to permit of proper angular positioning of the co-operative sharpening faces with respect to the blade or work and provide effective sharpening contact of said faces with the work.

A still further object of the present invention is to provide sharpening faces on the edges of the discs of a form to produce effective sharpening action when a blade is drawn in either direction through the recess and across the discs, and to improve devices

of this character in sundry details hereinafter pointed out.

A preferred embodiment of the invention for accomplishing these and other objects is shown for illustrative purposes in the accompanying drawing, in which

Fig. 1 is a plan view of a knife or shear blade sharpener embodying my invention.

Fig. 2 is a side elevation of the device shown in Fig. 1 and illustrating the manner of attaching the sharpener to a table, shelf, door casing or other suitable support.

Fig. 3 is a longitudinal sectional elevation of the sharpener taken as indicated by the line 3—3 of Fig. 1.

Figs. 4 and 5 are diagrammatic views illustrating the angular positions that the sharpening faces of the discs may assume in operating on blades of varying degrees of thickness and depending on the angle of the cutting edge desired on the work.

Fig. 6 is a diagrammatic view of the invention illustrating the adaptability of its use to shear blades or the like.

In the illustrative embodiment shown, a bracket or frame 10 may be provided at opposite sides of the base portion 11 thereof with upright parallel flange portions 12, the said flange portions adjacent their free edges being provided with aligned openings adapted to receive a pair of shafts 13 in parallel relationship with respect to each other. Mounted on each of the said shafts, in a manner to rotate freely thereon, are a series or plurality of polygonal shaped discs 14, preferably of hexagonal form, and spaced apart from each other and from the upright flange portions 12 of the bracket 10 by suitably positioned spacing washers 15, the series of discs on the respective shafts being adapted to overlap at their adjacent edges in staggered relationship and in such a manner that the sharpening faces 16 of the discs on the respective shafts co-operate to form a V-shaped recess for receiving a knife blade or the like to be sharpened. The faces 16 of the discs are of flat transverse form adapted to provide a sharp right angular corner at their juncture with the sides of the discs. Thus, it will be observed that a cutting or sharpening action

will be produced on the blade or work by the discs whether the work is drawn through the recess in one direction or the other, thereby doubling the efficiency and effective life of the sharpener. If desired, the edges of the discs may be hardened to provide more durable and effective sharpening faces.

To limit the complete rotation of the discs 14, except as desired, the upright flanges 12 of the bracket 10 may be provided with apertures, preferably adjacent their central portion, for receiving removably a stop pin 17 shown in the present instance as an ordinary cotter pin adapted to extend between the flanges 12 in the plane of rotation of the greatest diameter of the discs, thereby preventing complete rotation of the discs, but permitting the discs to oscillate within desired limits even when the stop pin is in position. It will be observed that by such an arrangement, the effective co-operating sharpening faces of the respective series of discs forming the V-shaped recess such, for example, as the faces *a*, Figs. 2 and 3, may be movably secured against complete rotation and in co-operative relationship so long as they retain their sharpening efficiency, but when they have become dulled by continued use, the stop pin 17 may be withdrawn from the upright flanges 12 and the discs of the respective series rotated on the shafts 13 to bring, for example, the faces *b* into co-operative relationship, thereby presenting new or unused sharpening faces to the work, after which the stop pin 17 may be replaced in the apertures of the flanges 12 to retain the faces *b* in co-operative relationship until such time as it is desired to again shift or rotate the discs to present new or unused sharpening faces to the work. This procedure may be repeated as often as may be desired or until the efficiency of the sharpening faces 16 has been exhausted.

It will be observed also that in such a construction and arrangement the discs 14 are allowed sufficient rotary movement to provide for the relative positioning of the co-operative sharpening faces to adapt them to various types of blades and to provide effective sharpening contact of the faces 17 with the sides of the blade or work when pressure is applied thereto, and at the same time prevents unrestrained rotation of the discs, thereby enabling the user to obtain and utilize the full efficiency of the sharpening faces. This result can not be accomplished where the discs are free to rotate unrestrained in which case the positioning of the discs is beyond the control of the user and efficient co-operation of the sharpening faces can not be relied upon.

Referring to Figs. 4, 5 and 6, it will be noted that the median line of the blade *c* is off-set or remote from the center of the discs 14 and tangential to the line of rotation there-

of. By this arrangement a force exerted on the blade *c* in the direction of the arrow *d*, as the blade is drawn through the V-shaped recess, will tend to rotate the discs in the direction of the arrows *e*, thereby causing the sharpening faces 16 of the discs to approach and snugly impinge the sides of the blade to provide a most efficient sharpening contact therewith.

The base portion 11 of the bracket 10 may be provided with suitably positioned apertures 18 adapted to receive suitable fastening means, as, for example, the screws 19, for securing the device to a table, shelf, door casing, or other suitable support.

It will be observed from the foregoing description that the present invention provides a novel construction and arrangement wherein the co-operating sharpening faces of the discs are under the control of the user, thereby enabling the operator to utilize to the fullest extent the efficiency of the sharpening faces, and wherein the operative sharpening faces of the discs are positioned automatically with respect to the blade and forced against the sides of the blade to provide effective sharpening contact therewith.

Obviously, the present invention is not limited to the specific construction and arrangement shown and described but the same may be variously modified without departing from the spirit and scope of the invention as defined by the claims. Moreover, all the features of the invention need not be used conjointly, as the same may be used to advantage in variously different combination and sub-combinations.

What I claim as my invention and desire to secure by Letters Patent is:

1. In a blade sharpener, the combination of a frame, a plurality of polygonal discs rotatably mounted in said frame and having co-operable sharpening faces formed on their outer edges, the respective axes of said discs being positioned in substantially parallel relationship with respect to each other in a manner to permit the adjacent edges of the discs to overlap and be rotated toward each other when pressure is exerted on the co-operable sharpening faces, and unitary detachable means co-operable with the faces of all of said discs for limiting their rotation.

2. In a blade sharpener, the combination of a frame, a plurality of polygonal discs rotatably mounted in said frame and having co-operable sharpening faces formed on their outer edges, the respective axes of said discs being positioned in substantially parallel relationship with respect to each other in a manner to permit the adjacent edges of the discs to overlap and be rotated toward each other when pressure is exerted on the co-operable sharpening faces, and means mounted on said frame and co-operable with the faces

of the respective discs for limiting their rotation.

3. In a blade sharpener, the combination of a frame, a plurality of series of polygonal discs having sharpening faces formed thereon, said discs being rotatably mounted in said frame in a manner to position the sharpening faces of one series of discs in co-operable relationship with the sharpening faces of the other, and means mounted in said frame for limiting the rotation of said discs and readily removable therefrom for permitting the free rotation of the respective series of discs.

4. In a blade sharpener, the combination of a frame, a plurality of series of polygonal discs rotatably mounted therein, the axes of said series being positioned in parallel relationship with respect to each other and in a manner to cause the edges of one series of discs to overlap and lie in staggered relation with those of the other series, a plurality of sharpening faces formed on the edges of said discs, the sharpening faces of one series of discs being adapted to co-operate with those of the other series, and means co-operable with said faces of the respective series of discs for permitting a limited degree of rotation of said discs.

5. In a blade sharpener, the combination of a frame, a plurality of series of discs rotatably mounted therein, said discs having a plurality of sharpening faces formed thereon, said series of discs being positioned with respect to each other in a manner to bring the sharpening faces of the discs of the respective series into co-operable relationship to form a V-shaped recess adapted to receive a blade in a manner to rotate the discs toward each other and to force the sharpening faces of the discs of the respective series against the sides of the blade when pressure is applied thereto, and means intermediate said series of discs for limiting the rotation of said discs with respect to each other.

6. In a blade sharpener, the combination of a frame, a plurality of series of independently rotatable discs mounted therein, said discs having a plurality of sharpening faces formed thereon, said series of discs being positioned with respect to each other in a manner to bring the sharpening faces of the discs of the respective series into co-operable relationship to form a V-shaped recess adapted to receive a blade to be sharpened in a manner to rotate the discs toward each other and to force the co-operative sharpening faces of the discs of the respective series against the blade when pressure is applied thereto, and means mounted on said frame and co-operable with the respective series of discs for permitting a limited degree of rotation of said discs with respect to each other when such pressure is applied.

7. In a blade sharpener, the combination of a frame, a plurality of shafts mounted there-

in, a plurality of independently rotatable discs loosely mounted on said shafts, said discs having a plurality of sharpening faces formed thereon, the discs on one of said shafts being positioned with respect to the discs on the adjacent shaft in a manner to bring certain of the sharpening faces of the discs on the respective shafts into co-operable relationship to form a V-shaped recess adapted to receive a blade to be sharpened in a manner to rotate the discs of the respective shafts toward each other and to force the sharpening faces of the discs forming said recess against the sides of the blade when pressure is applied thereto, and means removably mounted in said frame and co-operable with the sharpening faces of the discs on the respective shafts for limiting the rotation of the said discs on said shafts with respect to each other.

8. In a blade sharpener, the combination of a frame, a plurality of shafts mounted therein in parallel relationship, with respect to each other, a plurality of independently rotatable discs loosely mounted on said shafts, means for spacing the discs on the respective shafts, said discs being provided with a plurality of straight sharpening faces of flat transverse form, the discs on one of said shafts being positioned with respect to the discs on the adjacent shaft in a manner to bring certain of the sharpening faces of the discs on the respective shafts into co-operable relationship to form a V-shaped recess adapted to receive a blade to be sharpened in a manner to rotate the discs of the respective shafts toward each other and to force the sharpening faces of the discs forming said recess against the sides of the blade when pressure is applied thereto, and means removably mounted in said frame intermediate said shafts and co-operable with the sharpening faces of the discs on the respective shafts for limiting the rotation of the discs on said shafts.

9. In a blade sharpener, the combination of a frame, a plurality of series of polygonal discs rotatably mounted therein, the axes of said series being positioned in parallel relationship with respect to each other in a manner to cause the edges of one series of discs to overlap and lie in staggered relation with those of the other series, a plurality of sharpening faces formed on the edges of said discs, the sharpening faces of one series of discs being adapted to cooperate with those of the other series in a manner to form a V-shaped recess adapted to receive a blade to be sharpened, means mounted on said frame and co-operable with the sharpening faces of the respective series of discs for preventing complete rotation of said series of discs and in a manner to permit a limited movement of the sharpening faces of the discs forming said V-shaped recess toward each other and toward

said blade when pressure is applied to the blade.

10. In a blade sharpener, the combination of a frame, a plurality of discs rotatably mounted in said frame and having co-operable sharpening faces formed on their outer edges, the respective axes of said discs being positioned in substantially parallel relationship with respect to each other in a manner to cause the adjacent edges of the discs to overlap and to be rotated toward each other when pressure is exerted on said cooperable sharpening faces, and means for preventing rotation of said discs beyond predetermined limits.

15 In testimony whereof I have signed my name to this specification, on this 22nd day of July A. D. 1926.
